UNITED STATES PATENT OFFICE.

GROVER GOODRICH TUTTLE, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DRILL-STEEL RETAINER.

1,414,234.

Specification of Letters Patent. Patented Apr. 25, 1922.

Application filed August 13, 1920. Serial No. 403,250.

To all whom it may concern:

Be it known that I, GROVER GOODRICH TUTTLE, a citizen of the United States, and a resident of Phillipsburg, Warren County, 5 New Jersey, have invented certain new and useful Improvements in Drill-Steel Retainers, of which the following is a specification.

This invention relates to drill steel retainers for rock drills, but more particularly to that type of retainer in which a yoke embraces the drill steel and is suitably held or clamped in position upon the front head of the machine.

15 Such yoke retainers are subjected to severe impact as the collar on the drill steel strikes the yoke and various devices have been employed to cushion or yieldingly hold the yoke to avoid breakage of the parts, some of 20 these devices including bolts and springs, but the breakage is difficult to overcome, and the more complex the parts, the greater the danger of breakage becomes.

The primary objects of the present invention are to simplify the retainer construction, and reduce the chances of breakage by avoiding the use of retainer bolts and supporting the yoke retainer from the front head of the machine by means of an arrangement of main and supplementary springs which cushion the yoke in both directions.

Another object of the invention is to supplement the expansive force of the main springs in holding the retainer, by means 35 of fluid under pressure, which may be the live pressure taken from the supply inlet of the machine. In such case, if the pressure fails for any reason, the main retainer springs still fulfill the function of exerting 40 pressure to cushion the yoke.

To these ends the invention is shown in its preferred form in the accompanying drawings, in which

Figure 1 is a side elevation of the front 45 head of a rock drill having my drill steel retainer applied thereto, a portion of the wall of one of the spring holding guides being shown broken away,

Figure 2 is a vertical sectional elevation 50 of the front head on the line 2—2 of Figure 3 looking in the direction of the arrows,

Figure 3 is a top plan view of the front head with the drill casing and front head bushing removed,

Figure 4 is a vertical sectional elevation 55 of a front head showing a modified form of the drill steel retainer,

Figure 5 is a detail view partly in section showing one form of bearing block for the ends of the yoke,

Figure 6 is a similar detail view showing another form of bearing block, and

Figure 7 is a detail perspective view showing a bearing block for the ends of the yoke in the form of a cylinder.

Referring to the drawings, A represents the front head of a rock drill having the nose piece B, adapted to receive the front head bushing C through which the drill steel D having the collar E, is adapted to extend 70 in position to receive the impact blows of the hammer. The front head is provided with the usual lugs F through which the side bolts G extend for clamping the cylinder and front head together. In this instance the front end 75 portion H of the cylinder casing is shown partly broken away to indicate the relation of the parts.

In accordance with my invention the front head is provided with spring seats J at opposite sides of the machine and main coiled springs K are supported on said seats. Spring holding guides L preferably in the form of sockets are also provided on the front head in longitudinal alignment with the seats 85 J and supplementary coiled springs O, which may be lighter than the main coiled springs K, are arranged in said guides L. The outer walls of the spring holding guides L are slotted as shown at P and a yoke retainer Q 90 bent at the portion R to embrace the drill steel, is provided with arms S having hook shaped ends T supported between the said sets of springs K and O so that the yoke retainer is cushioned in both directions. The 95 bent ends T of the yoke are slidable in the slots P in the spring holding guides, and bearing caps U are preferably provided over the opposed ends of the springs K and O so that the bent ends T of the yoke are held 100 between the said bearing caps instead of directly against the springs in order to avoid wear on the springs and aid in centering the yoke.

In assembling the parts the front head is 105 removed from the machine and the main coiled springs K are first inserted through the open ends of the spring holding guides

and placed on the seats J with the bearing caps U on the springs. The yoke retainer is then placed in position in the slots P and the supplementary springs O with their bearing caps are placed in position in the spring guides. The lugs V on the casing cover the apertures in the spring holding guides and form covers to hold the springs and yoke in position. The yoke is maintained in operative position, as indicated in full lines in Figure 1 by means of the depressions W in the faces of the spring seats J and the yoke may be swung into the position indicated in dotted lines in Figure 1, for removal of the 10 drill steel when desired. If desired, oiling apertures X may be provided in the walls of the spring seats J so that by oiling, the seats oil will reach the contact faces between the arms of the yoke and the depressions W 15 in the spring seats.

In the operation of the device it will be observed that the main coiled springs K take the shock of the impact of the collar E of the drill steel upon the yoke and cushion the 20 blow in that direction. The supplementary springs O cushion the yoke in the opposite direction and obviously need not be as strong as the main coiled springs K. By my construction I avoid the use of retainer bolts 25 and fastening devices therefor, and depend upon the springs for cushioning the yoke, but I guide the yoke and springs in the spring holding guides and on the spring 30 seats in a simple and efficient manner which 35 avoids breakage both of the springs and the yoke.

In the modification shown in Figure 4, the walls Y of the spring seats J are lengthened and in this instance form continuations of 40 the outer walls of the spring holding guides L. Somewhat lighter main coiled springs K' are shown seated on the spring seats J and bearing caps in the form of thimbles Z are placed over the main coiled springs K' 45 and extend within the walls of the spring seats. The object of this construction is to permit fluid under pressure to be supplied to the telescopic chambers formed by the spring seats and the bearing thimbles Z in order to 50 supplement the expansive force of the springs. In this instance the walls of the front head are provided with the passages a having ports b communicating with the interior of the spring seats through which 55 fluid under pressure may be supplied. This fluid under pressure may be the live pressure from the supply inlet of the machine and if the fluid pressure fails the springs K' still fulfill their function of cushioning the yoke. 60 The fluid pressure maintained within the bearing thimbles Z supplements the spring pressure, enables lighter springs to be used and aids in preventing breakage of the springs and breakage of the yoke. If desired, the chambers within the spring seats 65

J may be filled with oil or grease to further aid the cushioning of the yoke and prevent breakage of the springs.

In the modification shown in Figure 5, a bearing block c in the form of a ball having a square hole d is shown adapted to fit over the square bent end e of the yoke arm S', in this instance the yoke being formed of square stock instead of round stock. The bearing plug or ball c is preferably provided with a flat surface f adapted to bear on one of the bearing blocks U or to bear upon the bearing thimble Z. If desired the face g of the bent end e of the yoke could be riveted or otherwise rigidly secured in the bearing plug c. In using a yoke with bearing plugs c at each end, the bearing caps U for the supplementary springs O may be dispensed with if desired.

In the modification shown in Figure 6 the 85 bent end h of the yoke arm S' is tapered to fit the tapered hole j in the bearing block k, and the advantage of this construction resides in the fact that wear between the ends h of the yoke and the bearing plugs k is automatically compensated for, and will be taken up in the operation of the device.

In the modification shown in Figure 7, the bearing block o is of cylindrical form having a tapered aperture p arranged transversely 95 therethrough to receive the tapered end q of the yoke arm S which in this instance is shown formed of round stock.

I claim:

1. A drill steel retainer for rock drills, 100 comprising spring seats rigidly connected to opposite sides of the front head of the machine, main coiled springs supported on said seats, spring holding guides in the form of sockets on the front head in longitudinal alignment with the said seats, supplementary coiled springs arranged within said 105 sockets, and a yoke retainer for the drill steel having the ends of its arms extending through the sockets and supported between 110 said sets of springs and cushioned in both directions, whereby the said main coiled springs take the shock of impact of the steel on the yoke retainer.

2. A drill steel retainer for rock drills, 115 comprising spring seats at opposite sides of the front head of the machine, main coiled springs supported on said seats, spring holding guides in the form of sockets on the front head in longitudinal alignment with the said seats, said guides having longitudinal slots in their outer walls, supplementary coiled springs arranged in said guides, and a yoke retainer for the drill steel having the ends of its arms slidably supported in said 120 guide slots between said sets of springs and thereby cushioned in both directions.

3. A drill steel retainer for rock drills, 125 comprising spring holding guides and spring seats in longitudinal alignment at opposite 130

- sides of the front head of the machine, main coiled springs on said seats, supplementary coiled springs in said guides, bearing caps over the opposed ends of said springs, and a 5 yoke retainer for the drill steel having the ends of its arms supported between said sets of bearing caps and thereby cushioned by the springs in both directions.
4. A drill steel retainer for rock drills 10 comprising spring holding guides and spring seats in longitudinal alignment at opposite sides of the front head of the machine, main coiled springs on said seats, supplementary coiled springs in said guides, bearing caps 15 in the form of thimbles arranged over the ends of the said main coiled springs and extending within the walls of the spring seats, a yoke supported between said sets of springs, and means for maintaining fluid 20 pressure within said bearing thimble to supplement the expansive force of the main coiled springs.
5. A drill steel retainer for rock drills 25 comprising spring holding guides and spring seats in longitudinal alignment at opposite sides of the front head of the machine, main coiled springs on said seats, supplementary coiled springs in said guides, bearing caps in the form of thimbles arranged over the 30 ends of the said main coiled springs and extending within the walls of the spring seats, bearing caps over the ends of the supplementary springs, a yoke retainer for the drill steel, having the ends of its arms supported 35 between said sets of bearing caps, and means for maintaining fluid pressure within said bearing thimbles to supplement the expansive force of the main coiled springs.
6. A drill steel retainer for rock drills, 40 comprising spring holding guides and spring seats at opposite sides of the front head of the machine, coiled springs in said guides and on said seats, and a yoke retainer for the drill steel having the ends of its arms provided with bearing blocks supported between 45 said sets of springs whereby the yoke retainer is cushioned in both directions.
7. A drill steel retainer for rock drills, 50 comprising spring seats at opposite sides of the front head of the machine, main coiled springs supported on said seats, spring holding guides in the form of sockets on the front head in longitudinal alignment with the said seats and open at the inner end of the back head, said guides being adapted to 55 be closed at their inner ends by the cylinder casing of the machine, supplementary coiled springs arranged in said guides; and a yoke retainer for the drill steel having the ends of its arms supported between said sets of 60 springs and cushioned in both directions.
8. A drill steel retainer for rock drills 65 comprising spring holding guiding sockets and spring seats at opposite sides of the front head of the machine, main and supplementary coiled springs in said sockets, the main coiled springs being supported on said seats, a yoke retainer for the drill steel having the ends of its arms supported between said sets of main and supplementary springs and 70 cushioned in both directions, and means for maintaining fluid pressure within said sockets to supplement the expansive force of the main coiled springs.
9. A drill steel retainer for rock drills 75 comprising spring holding guiding sockets and spring seats at opposite sides of the front head of the machine, coiled springs in said sockets and on said seats, a yoke retainer for the drill steel having the ends of 80 its arms supported and cushioned on said springs, and means for maintaining fluid pressure within said sockets to supplement the expansive force of the springs.
10. A drill steel retainer for rock drills, 85 comprising coiled springs mounted on the front head of the machine, a yoke retainer for the drill steel having the ends of its arms cushioned by said springs, and fluid pressure means exerting pressure on said yoke 90 arms for supplementing the expansive force of said cushioning springs.
11. A drill steel retainer for rock drills, 95 comprising a retaining member for the drill steel and means for mechanically and pneumatically cushioning said retaining member.
12. A drill steel retainer for rock drills, 100 comprising a retaining member for the drill steel supported from the front head of the machine, and devices for mechanically cushioning said retaining member including additional pneumatic means supplementing the said mechanical cushioning devices.

In testimony whereof I have signed this specification.

GROVER GOODRICH TUTTLE.
